UNITED STATES PATENT OFFICE

121,491

DESIGN FOR A SPOON OR ANALOGOUS ARTICLE

Aram R. Kalashian, Newburyport, Mass., assignor to Towle Manufacturing Company, Newburyport, Mass., a corporation of Massachusetts

Application March 13, 1940, Serial No. 90,899

Term of patent 14 years

To all whom it may concern:

Be it known that I, Aram R. Kalashian, a citizen of the United States, residing at Newburyport, in the county of Essex and Commonwealth of Massachusetts, have invented a new, original, and ornamental Design for a Spoon or Analogous Article, of which the following is a specification, reference being had to the accompanying drawing, forming a part thereof.

In the accompanying drawing, Figure 1 is a view of the front face of a spoon showing my new design; and Figs. 2 and 3 are sectional views

taken at the lines 2—2 and 3—3, respectively, of Fig. 1.

The essential features of my design reside in the parts shown in full lines.

The design is delineated as embodied in the handle of a spoon but the design may also be embodied in or applied to other handles of like nature.

I claim:

The ornamental design for a spoon or analogous article, substantially as shown and described.

ARAM R. KALASHIAN.
